UNITED STATES PATENT OFFICE.

CHARLES DOERING, JR., OF CHICAGO, ILLINOIS, ASSIGNOR TO THOMAS E. BARTON, OF WASHINGTON, DISTRICT OF COLUMBIA.

DESIGN FOR A BABY-BUGGY.

49,537.

Specification for Design.

Patented Aug. 22, 1916.

Application filed February 28, 1916. Serial No. 81,072. Term of patent 7 years.

To all whom it may concern:

Be it known that I, CHARLES DOERING, Jr., a citizen of the United States, residing at Chicago, in the county of Cook and State of Illinois, have invented a new, original, and ornamental Design for a Baby-Buggy, of which the following is a specification, reference being had to the accompanying drawing, forming a part thereof.

In the drawing the figure illustrates my

new design of baby buggy in perspective, looking toward the front end thereof.

I claim:—

The ornamental design for a baby buggy as shown.
